J. H. PHILLIPS.
SPRING HAMMER.
APPLICATION FILED AUG. 22, 1911.

1,053,744.

Patented Feb. 18, 1913.

UNITED STATES PATENT OFFICE.

JOHN H. PHILLIPS, OF OKLAHOMA, OKLAHOMA.

SPRING-HAMMER.

1,053,744.

Specification of Letters Patent. Patented Feb. 18, 1913.

Application filed August 22, 1911. Serial No. 645,380.

To all whom it may concern:

Be it known that I, JOHN H. PHILLIPS, a citizen of the United States, and a resident of Oklahoma, in the county and State of Oklahoma, have invented a new and Improved Spring-Hammer, of which the following is a full, clear, and exact description.

My invention relates to a portable hammer and more particularly relates to a mechanically-actuated hammer.

The invention is designed to be an improvement over the hammer fully described in my co-pending application, Serial No. 533,867, filed December 18, 1910.

15 An object of the present invention is to provide a hammer automatic in its action and which will receive its direct force from a compressible spring.

20 A further object of the invention is to vary the tension on the spring.

A further object is to quickly vary the intensity of blow delivered by the hammer while in operation.

A still further object of the invention is 25 to provide a device of the above-indicated character, which possesses relatively few parts which might get out of order, which is simple in its construction and operation, and which may be quickly and accurately 30 adjusted for its various functions.

With the above and other objects in view, as will more fully hereinafter appear, the present invention consists in certain novel details of construction and arrangement of 35 parts hereinafter fully described, illustrated in the accompanying drawings, and more particularly pointed out in the appended claims.

Reference is to be had to the accompanying drawings, forming a part of this specification, in which similar characters of reference indicate corresponding parts in all the views, and in which—

Figure 1 is a longitudinal transverse sectional view showing a preferred embodiment of my invention; Fig. 2 is a transverse sectional view taken on the line 2—2 of Fig. 1; Fig. 3 is an enlarged detail showing the connection between the piston rod and the 50 spring; and Fig. 4 is a transverse sectional view taken on the line 4—4 of Fig. 1.

Rigidly mounted at one end of the barrel 1, is a handle 2 of any preferred construction, and secured to the opposite end of the 55 barrel, by means of a cap 3, in screw-

threaded connection with the barrel, is a tool 4 having a cylindrical shank 5 inserted in a sleeve 6 disposed within the bore 7 of the barrel 1. Interposed between the outer end of the sleeve 6 and a shoulder 8 on the 60 tool 4, is a washer 9, which washer is held in position by the flange 10 of the cap 3. Slidably mounted in the barrel 1 adjacent the inner end of the tool, is a plunger 11, which is adapted to reciprocate in the barrel 1. 65 The end of the plunger 11 opposite the tool 4, is provided with a head 12 connected to the body of the plunger by means of a stem 13. Normally bearing upon the head 12, is a follower 14, from opposite sides of which 70 project pins 15 sliding in slots 16 extending through opposite sides of the barrel 1, and permitting a limited movement of the follower 14. Projecting toward the handle from said follower is a stud 17, surrounding 75 which stud and bearing on the follower 14, is one end of a coiled compression spring 18, the other end of which surrounds the screw-threaded end 19 of a bolt 20, which bolt is 80 rotatably mounted in the handle 2 and is actuated by means of a thumb screw 21. The end of the spring opposite the end bearing on the follower 14 bears on a nut 22 in screw-threaded engagement with the bolt 20, so that by rotating the bolt, the nut will be 85 advanced along the same, varying the tension of the spring 18. To prevent the nut from rotating, a pin 23 projects from the periphery of the same and slides in the slot 24 in the inner bore of the barrel. 90

In order to compress the spring 18 to draw the plunger 11 away from the tool 4, a cam wheel 25 having a plurality of cam teeth 26 is rotatably mounted within a casting 27 and keyed to a shaft 28, which shaft 95 may be rotated by hand but preferably is rotated by any suitable mechanical means.

It will be seen that the spring 18 will force the head 12 into engagement with the teeth 26. These teeth revolving in the direction indicated by the arrow, will engage the head 12, force the plunger 11 away from the tool 4, and at the same time, compress the spring 18. As the teeth 26 slip by the head 12, the latter will be free to respond to the action of the spring 18, said spring then suddenly forcing the plunger 11 into engagement with the tool 4. 105

The tool is held against the work by means of the handle 2, which may be used 110

as a breast plate, or it may be supported by any other suitable means. The effect of the teeth engaging the head 12 will be to reciprocate the plunger 11, causing a series of 5 rapid sharp blows to be impressed on the tool 4. Should it be desired while working the device, to vary the intensity of the blows made by the tool 4, the cam-wheel 25 is brought closer to the head 12, thereby causing 10 the plunger to travel a greater distance under the influence of the spring 18 before it strikes the tool and is subsequently operated by the next succeeding tooth of the cam wheel. One means for varying the location of this cam-wheel is disclosed, and 15 consists in the mounting of the casing 27 in two parts, as shown more particularly in Fig. 2, the lower portion 29 being formed into opposing semi-cylindrical parts co-acting 20 to inclose therebetween the barrel 1, which parts are held in position by screws 30 or other suitable fastening means, and the casing is held in upright position by means of a guide plate 31 mounted in the 25 lower portion of the casing 27 and extending partly into the longitudinal slot 32 in the lower portion of the barrel 1 and opposite the slot 33 through which projects the teeth 26 of the cam-wheel 25. It will be seen that 30 by this connection the casing 27 and the contained ratchet 25 are slideable longitudinally on the barrel 1, to vary the engagement of the teeth 26 with the head 12.

In order to retain the casing in the desired position, and at the same time, to facilitate the adjustment of the same, an arm 34 has one end pivoted at 35 to the casing 27, the other end of which extends at right angles to the arm 34, to form a handle 351 35 extending substantially parallel to the gripping portion 36 of the handle 2. By this means the gripping portion 36 and the handle 351 may be grasped with one hand. The inner edge of the arm 34 has a series of 40 teeth 37 projecting therefrom, which teeth are adapted to engage a toothed ring 38 rigidly mounted on the barrel 1, adjacent its connection with the handle 2. The arm 34 is maintained in engagement with the ring 38 by means of a leaf spring 39, having one 45 end 40 rigidly attached to the handle 2 and having its free end 41 bearing on the outer edge of the arm 34. By drawing the handle 351 toward the handle 2 the cam wheel will be adjusted toward the spring, thereby increasing the length of the stroke 50 of the plunger, and this adjustment may be effected while the device is in operation.

Having thus described my invention, I

claim as new and desire to secure by Letters 60 Patent:

1. In a device of the class described, the combination with a barrel, of a tool adapted to reciprocate in said barrel, a plunger adapted to operate said tool, a member having a plurality of teeth thereon adapted to intermittently actuate said plunger in one direction, a spring for operating said plunger in the opposite direction, and means to adjust the toothed member with respect to 70 said spring while the device is in operation to vary the stroke of the plunger.

2. In a spring hammer, a barrel having a handle rigidly attached to one end thereof, a reciprocating member mounted in said 75 barrel, a head, a stem connecting said head and reciprocating member, a casing slidably mounted on said barrel, a cam wheel journaled in and housed by said casing and rotating opposite said stem, said cam wheel 80 having teeth thereon adapted to engage said head, to move the reciprocating member in one direction, a coil spring compressed by the movement of said head in said direction, and an arm pivoted to said casing, said arm 85 having a handle coacting with said barrel handle, whereby the handle on the arm and the handle on the barrel may be simultaneously grasped, to move said cam wheel into closer engagement with said head. 90

3. In a spring hammer, a barrel having a handle rigidly attached to one end thereof, a reciprocating member mounted in said barrel, a head, a stem connecting said head and reciprocating member, a casing slidably 95 mounted on said barrel, a cam wheel journaled in and housed by said casing and rotating opposite said stem, said cam wheel having teeth thereon adapted to engage said head, to move the reciprocating member in 100 one direction, a coil spring compressed by the movement of said head in said direction, an arm pivoted to said casing, said arm having a handle coacting with said barrel handle, whereby the handle on the arm and the handle on the barrel may be simultaneously 105 grasped, to move said cam wheel into closer engagement with said head, and spring-pressed means retaining said arm in engagement with said barrel, to maintain 110 said casing in adjusted position.

In testimony whereof I have signed my name to this specification in the presence of two subscribing witnesses.

JOHN H. PHILLIPS.
